UNITED STATES PATENT OFFICE.

CARL HORIX, OF CHICAGO, ILLINOIS.

DESIGN FOR A COMBINED CALENDAR, FOUNTAIN-PEN HOLDER, AND RECEPTACLE.

Application filed April 11, 1927. Serial No. 21,537. Term of patent 3½ years.

To all whom it may concern:

Be it known that I, CARL HORIX, a citizen of the United States, residing at Chicago, in the county of Cook and State of Illinois, have invented a new, original, and ornamental Design for a Combined Calendar, Fountain-Pen Holder, and Receptacle, of which the following is a specification, reference being made to the accompanying drawing, forming a part thereof.

In the drawing, the figure is a perspective view of a combined calendar, fountain pen holder and receptacle, showing my new design.

I claim:

The ornamental design for a combined calendar, fountain pen holder, and receptacle, as shown.

Chicago, Illinois, Apr. 8, 1927.

CARL HORIX.
